CLAIM

The ornamental design for a tray for paint roller and brush, as shown and described.

DESCRIPTION

FIG. 1 is a perspective view of a tray for paint roller and brush, showing our new design;

FIG. 2 is a front elevational view thereof;

FIG. 3 is a rear elevational view thereof;

FIG. 4 is a side elevational view, the opposite side being a mirror image thereof;

FIG. 5 is a bottom plan thereof; and

FIG. 6 is a top plan view thereof.
